United States Patent Office.

G. S. GARTH, OF MILL HALL, PENNSYLVANIA.

Letters Patent No. 31,621, dated September 1, 1868.

IMPROVED WAGON-AXLE.

The Schedule referred to in these Letters Patent and making part of the same.

TO ALL WHOM IT MAY CONCERN:

Be it known that I, G. S. GARTH, of Mill Hall, in the county of Clinton, and State of Pennsylvania, have invented a new and useful Improvement in Wagon-Axes; and I do hereby declare that the following is a full, clear, and exact description thereof, which will enable others skilled in the art to make and use the same, reference being had to the accompanying drawings, forming part of this specification, in which—

The drawing represents a side view of an axle-skein, provided with my improvements.

Similar letters of reference indicate like parts.

The object of this invention is to provide the means for lessening the friction of the hub on the axle-arm, and also to strengthen the latter at the shoulder.

It consists of two frictional bands, one of which is formed with a dove-tailed annular slot, fitting upon a dove-tailed collar, formed on the axle-arm at the shoulder of the same. The bands are cast on the axle-arm, and are of any suitable anti-friction metal, as brass, composition, or Babbitt-metal, so called. To confer greater strength to the shoulder, I also employ a separate band, *d*, of iron or other metal, which encircles the raised portion of the band *b* and the shoulder *f*.

The collar *e* may be made of any suitable dove-tailed character.

I desire to be understood as not limiting myself to the precise form of the bands, as they may be variously modified without departing from the principle of my invention.

I am aware of the patent granted to Thomas Falvey, dated February 5, 1867, for an axle-skein, provided with collars of different material from that composing the body of the skein, said collars being cast on irregular screw-threads, but as this forms no part of my invention, I do not wish to claim it; but, having thus described my invention—

I claim as new, and desire to secure by Letters Patent—

1. An axle provided with collars *a* *b* of anti-friction metal, the latter (*b*) being cast on to a dove-tailed collar, *e*, which is formed on or fitted to the axle, as herein shown and described, when the raised portions of the band *b* and shoulder *f* are encircled by a strengthening-band, *d*, as set forth for the purpose specified.

2. The strengthening-band *d* encircling the raised portions of the band *b* and shoulder *f*, substantially as herein shown and described for the purpose specified.

The above specification of my invention signed by me, this 6th day of June, 1868.

G. S. GARTH.
